UNITED STATES PATENT OFFICE.

WILLIAM BUTTLER, OF REDKEY, INDIANA.

DESIGN FOR A TUMBLER.

SPECIFICATION forming part of Design No. 29,813, dated December 20, 1898.

Application filed October 28, 1898. Serial No. 694,844. Term of patent 7 years.

To all whom it may concern:

Be it known that I, WILLIAM BUTTLER, of Redkey, county of Jay, and State of Indiana, have invented a new and original Design for 5 Tumblers, of which the following is a full, clear, and exact description, reference being had to the accompanying drawings, forming part of this specification, in which—

Figure 1 is a side elevation of a drinking cup or tumbler embodying my design, and Fig. 2 is a top plan view of the same.

The leading feature of my design consists in a cup or tumbler having near its upper end an annular outwardly-swelled portion 5 and above the same a projecting lip of smaller diameter than the swelled portion.

In the drawings, 2 represents the cup or tumbler, having near its upper end the annular outward swell 3 and above the same a projecting lip 4 of smaller diameter than the 20 swelled portion below it.

I claim—

The design for a tumbler; substantially as herein shown and described.

In testimony whereof I have hereunto set 25 my hand.

WILLIAM BUTTLER.

Witnesses:

DANIEL WILT,
E. L. ASBERAFT.
